UNITED STATES PATENT OFFICE.

ADAM REED, OF YAKIMA, WASHINGTON.

SHIELD.

1,403,867.

Specification of Letters Patent. Patented Jan. 17, 1922.

Application filed September 7, 1920. Serial No. 403,465.

To all whom it may concern:

Be it known that I, ADAM REED, a citizen of the United States, residing at Yakima, in the county of Yakima and State of Washington, have invented new and useful Improvements in Shields, of which the following is a specification.

My present invention pertains to improved, adjustable bunion shields, for the protection and relief of pressure and friction of enlargements of the great and little toes that are commonly known as bunions.

The invention also contemplates the provision in a device of the character set forth of means whereby the shield may be readily shifted from one to the other enlargements of the said toes.

The invention further contemplates the provision of a shield for use in connection with what is known as metatarsala which is the dropping down of the heads of the metatarsals and the phalanges under the foot. At the present time, a support made of leather and steel is worn in the shoe in the manner of an arch support which raises a portion of the foot to push these heads back into place, whereas my shield may be used for the purpose by placing the same under the heads of these bones.

The invention further contemplates the provision of a shield that may be used to prevent the pressure of the shoe on a corn or callous, and the shield may be readily adjusted to all shapes and sizes of feet with but a slight amount of effort on the part of those practicing the invention.

Other features and advantageous characteristics of my novel invention will be fully understood from the following description and claim when the same are read with the drawings accompanying and forming part of this specification in which:

Figure 1 is a view illustrating my novel shield as applied to the foot of a person.

Figure 2 is a side elevation of a foot and showing the position my shield assumes with respect to the foot.

Figure 3 is a sectional view of the shield per se.

Figure 4 is an inverted plan view of the shield.

Similar numerals of reference designate corresponding parts in all the views of the drawings.

My novel shield comprises a portion 1 of soft lamb's-wool felt or any other suitable material compatible with its purpose and in constructing the shield I bevel the edges thereof as indicated by 3, but in this connection I would have it distinctly understood that the portion 4 of the shield that abuts the bunion B, is square as shown.

A slot 7 is cut in one side 3 of the felt and into said slot I thread one end of an elastic tape 6 and secure said end within the felt 1 by means of stitches 8.

The other end of the strap or elastic 6 is then cut off after it is determined approximately the width of the average foot as shown in the drawings.

Arranged in a permanent manner on the upper surface of the felt 1 is a buckle 5 through which the free end of the tape 6 is passed and through the medium of which the shield may be held in a proper position and readily adjusted with respect to the foot of the wearer and in this connection it will be noted that the free end of the tape passes under the first bar of the buckle 5, over the central bar and under the third bar and this will securely hold the tape and preclude bunching of the shield or prevent the same from becoming bundlesome, and at the same time will permit adjustment of the device to any size or shape of foot.

As clearly appears in the drawings, it will be noted that I secure to the inner surface of the felt a portion 2 of soft leather and this prevents chafing of the skin and renders the shield more durable.

It will be gathered from the foregoing, because of its construction my novel shield may be readily removed upon retiring and easily applied when dressing the feet and when properly applied the shield will be raised a little above the height of a bunion or the like and will remove all pressure and friction upon the bunion as well as fill in the hollow that is present surrounding the bunion.

I would distinctly have it understood that the invention is in no sense of the word a cure for bunions or the like but it is intended to relieve all ache and soreness due to pressure on the bunion and notwithstanding its character the invention will add materially to the appearance of the shoes of those practicing my invention.

Having described my invention, what I claim and desire to secure by Letters Patent is:

In a shield for the purpose set forth, the combination of an inner portion formed of soft leather and having one of its sides rounded, a portion of soft felt arranged on the first-named portion, and having three beveled edges and one straight edge, and a buckle adapted to rest upon the soft felt

material, and a tape secured to the soft felt material and adapted to have its free end engaged by the buckle.

In testimony whereof I have hereunto set my hand in presence of two subscribing witnesses.

ADAM REED.
